EDGAR A. MILLER AND CLEVELAND A. JAMES, OF PHILADELPHIA, PENNSYLVANIA.

SIGNAL DEVICE.

Application filed January 4, 1924. Serial No. 684,311.

The invention has for an object the provision of a danger signalling device for highways and traffic purposes, the same being so constructed that it is rendered temporarily luminous by reflected light rays from the approaching vehicle, to the occupants of which the signal is to be given.

More especially, our device is intended to be installed as a cautionary signal at dangerous points along a highway, as at bad curves, intersecting roads, or at railroad crossings; and moreover, the device is further adapted for use as a tail light for automobiles, wagons or other vehicles to prevent collisions from fast moving vehicles in the rear. In all cases, the device depends for its illumination upon extraneous light and, in practical use, from the head lights of the approaching vehicle which is to be warned of coming danger.

By the employment of a danger or cautionary signal of this character, no attention or care is required to maintain it in operative condition and hence it is not only inexpensive to maintain in use, but it is thoroughly reliable in operation.

In some forms of signal apparatus of this general character, the reflected light is faint and insufficient for reliance on dark and foggy nights, and especially where the luminosity of the headlights of the approaching vehicle is of a low candle power; and in other cases, the reflected light beam is so deflected away from the approaching vehicle or dispersed to such extent as to render it inadequate to meet the requirements as to efficiency.

By the employment of our improved construction of signal device, the above defects are overcome and the light beam is reflected directly back with full intensity upon the approaching vehicle and brilliant in red or other color significant of the danger or necessity for caution.

With the above and other objects in view, the nature of which will be more fully understood from the description hereinafter, the invention consists in the novel construction of signal devices, as hereinafter more fully described and defined in the claims.

Referring to the drawings: Fig. 1 is a diagram showing the course of light rays striking mirrors placed at an angle of more than ninety degrees with one another; Fig. 2 is a similar diagram with the mirrors arranged at an angle of ninety degrees with

one another; Fig. 3 is a diagram in plan of a series of concentric mirrors having their adjacent reflecting surfaces arranged at angles of ninety degrees with one another and 60 with circular transparent ribs interposed between the mirrors of each pair and embodying the broader principles of our invention; Fig. 4 is a cross sectional diagram through the same; Fig. 5 is a front view of a danger signal embodying the features of construction of Figs. 3 and 4 showing the zone of illumination by the use of colored transparent ribs; Fig. 6 is a similar view to Fig. 5 but with the use of colored translucent ribs 70 whereby an increased area of illumination is secured; Fig. 7 is a front or face view of a danger signal device constructed in accordance with our invention; Fig. 8 is a transverse section of the same taken on line 75 8-8 of Fig. 7; and Fig. 9 shows a modification of the invention.

Rays of light 4, 4, striking a pair of mirrors 1, 1, placed at an angle greater than ninety degrees with one another, as shown in 80 Fig. 1, will not be reflected in lines parallel with their path of incidence and hence will be dispersed; but rays of light 4, 4, striking a pair of mirrors 2, 2, placed at an angle of ninety degrees, as shown in Fig. 2 will be 85 reflected back in parallel lines. Rays from any source within the planes of the mirrors 2, 2, and in a plane at right angles to the line of intersection of the planes of the mirrors, 2, 2, will be reflected back to their source; 90 so that a pair of such mirrors whose planes of reflection are placed vertically one above the other will have a wide horizontal range of reflection, and a pair of such mirrors whose planes of reflection are placed horizontally side by side will have a wide vertical range of reflection. Placed either way, the range of such a pair of mirrors in the direction of or parallel with the intersection of the planes of the mirrors, is limited to the 95 length of the mirrors. A series of concentric mirrors 3, 3, (Figs. 3 and 4), placed at angles of ninety degrees with one another will be not only a combination of horizontally and vertically placed mirrors, but of 100 mirrors placed at all angles between the horizontal and the vertical, so that a series of concentric mirrors so constructed will reflect back to its source light from any source within the reflecting planes of the mirrors. 110

The portion of such a combination of concentric mirrors that would reflect light back

to any source when not directly in front of it is that area of the mirrors lying along a line of intersection, such as 7, of the plane of the mirrors with a plane normal to the plane of the mirrors, and passing through the source of the light, as in Fig. 5. This area of reflection 8 is comparatively small. A rib 6 (Figs. 3 and 4) of colored transparent material placed between the mirrors of 10 each pair will color the reflected light, so that the area 8 will appear colored from a position adjacent to the source of the light. But this area 8 is, as before stated, comparatively small, and a combination of the 15 concentric mirrors with colored transparent ribs is, therefore, only of use in providing for both vertical and transverse capacities for reflection.

It will now be understood that when the 20 rib 6 is of highly transparent material offering no serious resistance to passage of the light rays and the plane of the face of the signal device is exactly at right angles to the source of light so that every portion of the 25 mirrors operate to fully reflect the light, the device as a whole would be quite efficient; but this is only an ideal condition, as the signal device is fixed and the automobile providing the source of light is approaching 30 at almost any angle and under those actual conditions, the efficient operation is not possible. This objection would be still more apparent in cases where the signal device was movable as when constituting a tail light 35 or signal of another vehicle and especially when not traveling on a narrow roadway.

If, however, we substitute for the colored transparent rib, a rib of colored translucent material, such as colored celluloid having 40 some degree of light obstruction, then the luminous or light reflected area will be very greatly increased, as graphically shown at 8^a in Fig. 6. In fact, the entire reflecting area of the device will be colored. This result is 45 achieved for the reason that, while with a transparent rib 6 only the rays striking along the plane of intersection 7 are reflected back to their source, with a translucent rib 10, (Fig. 8), it, itself, is highly illuminated by 50 the light reflected upon it from the mirrors, and the reflection of said highly illuminated rib appears over the entire area of the mirrors and is reflected back as a circular area or ball of brightly colored light, thus operating 55 as a highly efficient danger signal. To achieve this desired result, it is not necessary to place the mirrors at exact right angles, but the angles may be much smaller, if so desired, without seriously affecting the 60 operative efficiency.

When the circular colored rib 10 is translucent, not only is the transmitted light passing through it reflected back to the source, as in Fig. 5, but the highly illuminated 65 faces of this translucent rib reflects back

upon the same mirrors the light received from them and they, in turn, reflect it back to the source; and it is to be kept in mind that this reflection from the illuminated rib is directed to many different portions of the 70 mirrors than those from which the light was originally received. It is for this reason that the entire signal device reflects back a brilliant colored light for its whole area instead of a relatively small area, irrespective of the position of the approaching light source. Because the device has this possibility of reflection of color from the illuminated translucent rib instead of using the 75 rib only as a colored transparent element, the 80 conical reflectors are given capacities which otherwise they would not have, that is to have capacity to reflect the colored light for the greater part or all of their circumferential area. While we have referred to the 85 function of a single circular colored rib and its associated circular reflectors having inclined reflecting surfaces, it will be manifest that the advantages will be enhanced 90 many fold by increasing the number of concentric reflectors and ribs; and in commercial practice, a plurality of ribs and reflectors are employed, the latter being preferably twice as many as the former.

We will now refer more specifically to a 95 commercial form of our improved signal device, as shown in Figs. 7 and 8. The front of the reflector is of glass pressed or molded in one piece, and is a combination of the annular concentric mirrored surfaces 3, 3, with 100 the annular hollow transparent ribs 14, 14, in which ribs are placed the circular bands or ribs 10, 10, of colored translucent material. The sides of the ribs 14, 14, preferably flare outward and the outer extreme annular surface 15 is cut off at a V shaped angle, so that the white light reflected from the outer 105 surface of the glass is thrown outward to the sides rather than in a line at right angles to the plane of the reflector, whereby the 110 white light does not interfere with the colored reflection of the translucent ribs comprised of the parts 10 and 14. The angle between the annular mirrors of a pair may vary from sixty to ninety degrees. The glass 115 front has a backing 12 of wood, cement, plaster of Paris, vulcanite fiber, or other composition, or other suitable material poured or molded, and if the latter, affixed by adhesive means, as at 11. The whole is 120 enclosed in a sheet metal case 13, as shown, leaving only the reflecting area exposed.

While the device, as shown in Figs. 7 and 8, may be directly arranged in position and exposed when used, nevertheless, if desired, 125 it may be protected and kept clean by being placed within a shelter with a glass window, or such a window (not shown) may be provided on the device itself.

The signal device, as a whole, may be se- 130

cured, where needed, in fixed position in a suitable location at the side of the roadway, as by being attached to a post; and in case of use upon the rear of a vehicle, it may be 5 provided with any suitable attaching means, but such means are not material to our invention and hence have not been illustrated.

While we prefer that the angle, between the reflecting surfaces constituting a pair, 10 shall be ninety degrees, it will be readily understood that this is because, when directly approaching the signal device in a line at right angles to the plane of its concentric reflectors, a maximum efficiency will be secured; but because the reflecting surfaces and ribs are annular and the light rays from the source will, in most instances, vary from such ideal alinement, the angle made between the reflecting surfaces may be less than 15 ninety degrees, and especially so in view of the fact that the light reflections from mirrors to colored rib and rib to mirror may involve different courses of travel before being projected back to the source. For this 20 reason, we do not restrict ourselves as to angles less than ninety degrees, though no angle materially greater than ninety degrees 25 may be employed.

In the particular illustrated example of 30 our device, we have shown the employment of two annular colored translucent ribs, but as before stated, a greater number of ribs and reflectors may be employed; and similarly, it will be understood that one pair 35 of annular inclined reflecting surfaces and one colored rib structure will suffice for the broader example of our invention. In cases where more than one such set is employed and preferably when three or more 40 sets are employed, we may change the color of the outermost rib by employing a green translucent band 10, with the result that by so doing, the brilliancy of the enclosed red 45 reflections will be enhanced and more clearly defined. Of course, the particular colors employed is not a material factor, though we prefer to use red as the dominant color, as it is appropriate to "danger" and is far 50 more brilliant to the sight than green and hence more readily perceived by an occupant of a fast moving automobile.

It is further to be understood that while the annular reflectors and ribs are best made as circular, we do not restrict ourselves in 55 this respect, because these parts may be more or less polygonal, since a circle is only a polygonal with an indefinite number of sides and it is manifest that our improvements may be efficiently adapted to a polygonal 60 form, for example, of eight or more sides as found suitable.

Furthermore, while it is desirable that the colored annular rib material 10 be arranged to exactly divide the angle between

the reflecting surfaces 3, 3, we do not restrict ourselves to that detail, in view of the fact that said rib is translucent or tending to some degree of opaqueness, and hence the reflected light from one mirror surface is not dependent for its final reflection back 65 to the source that it shall pass freely through the rib to the other mirror of the pair, as would be the case were the rib wholly transparent. While we have referred to the use of celluloid as suitable for the annular 70 colored ribs, other materials may be employed, such as prepared paper, tracing cloth, vellum, sheet gelatine, etc., when colored, by way of examples.

It will now be apparent that we have devised a novel and useful construction which embodies the features of advantage enumerated as desirable, and while we have in the present instance shown and described the preferred embodiment thereof which has 80 been found in practice to give satisfactory and reliable results, it is to be understood that we do not restrict ourselves to the details, as the same are susceptible of modification, in various particulars without departing 85 from the spirit or scope of the invention. 90

Having now described our invention, what we claim as new and desire to secure by Letters Patent is:

1. A signal device which is illuminated by light from another and distant source and reflects said light back to the source in modified condition, consisting of a reflector composed of a plurality of concentric reflecting surfaces arranged in pairs respectively inclined at an angle to each other to form an annular V shaped reflecting groove, and an annular rib extending outwardly from the bottom of each of the V reflector 100 grooves to substantially divide said grooves into two annular reflecting parts and said annular ribs being of colored translucent material adapted to receive and permit the passage of part of the reflected light from each 105 of the reflecting surfaces immediately disposed on opposite sides of the annular ribs.

2. A signal device which is illuminated by light from another and distant source and reflects said light back to the source in modified condition, consisting of a reflector composed of two concentric reflecting surfaces inclined at an angle to each other to form an annular V shaped reflecting groove, and an annular rib extending outwardly 115 from the bottom of the V reflector groove to substantially divide said groove into two annular reflecting parts and of colored material adapted to receive and permit the passage of part of the reflected light from 120 each of the reflecting surfaces, and wherein further, the annular reflecting surfaces are made of glass coated to form mirrors and 125

having between them a transparent annular hollow glass rib in which is arranged the annular colored translucent rib.

3. The invention according to claim 1, wherein further, the annular colored rib is arranged within and so as to substantially bisect the V shaped reflector groove throughout its circular form.

4. A signal device which is illuminated by light from another and distant source and reflects said light back to the source in modified condition, consisting of a reflector comprised of a plurality of concentric annular reflecting surfaces all fully exposed from the front, the adjacent surfaces inclined in opposite directions to provide a plurality of pairs of concentric reflecting surfaces forming a plurality of annular V shaped reflecting grooves, respectively of increasing diameter, and a circular rib extending outwardly from the bottom of each of the V reflector grooves to substantially divide said grooves into annular inclined reflecting parts, said ribs being of colored translucent material and each adapted to receive the light from their respective pairs of reflecting surfaces.

5. A signal device which is illuminated by light from another and distant source and reflects said light back to the source in modified condition, consisting of a reflector comprised of a plurality of concentric annular reflecting surfaces all fully exposed from the front, the adjacent surfaces inclined in opposite directions to provide a plurality of pairs of concentric reflecting surfaces forming a plurality of annular V shaped reflecting grooves respectively of increased diameter, and an annular rib extending outwardly from the bottom of each of the V reflector grooves to substantially divide said grooves into annular inclined reflecting parts, said ribs being of colored translucent material and each adapted to receive the light from their respective pairs of reflecting surfaces, and wherein further, the outermost annular colored rib is of a

different color from those of the remaining annular colored ribs.

6. A signal device which is illuminated by light from another and distant source and reflects said light back to the source in modified condition, consisting of a reflector comprised of a plurality of concentric annular reflecting surfaces all fully exposed from the front, the adjacent surfaces inclined in opposite directions to provide a plurality of pairs of concentric reflecting surfaces forming a plurality of annular V shaped reflecting grooves respectively of increasing diameter, and a circular rib extending outwardly from the bottom of each of the V reflector grooves to substantially divide said grooves into annular inclined reflecting parts, said ribs being of colored translucent material and each adapted to receive the light from their respective pairs of reflecting surfaces, and wherein further, all of the plurality of reflecting surfaces are formed of mirrored glass in an integral structure and said glass structure provided with means for holding the several colored annular ribs in position.

7. A signal device which is illuminated by light from another and distant source and reflects said light back to the source in modified condition, consisting of a plurality of reflecting surfaces set at an angle to each other, said reflecting surfaces arranged about a central point in a circle so that the relative angles between the reflecting surfaces at different places about the center assures different angles with reference to a horizontal plane when the device is in use, and colored translucent means arranged in the spaces between the reflecting surfaces through which the reflected light is caused to pass before being reflected back to the source.

In testimony of which invention, we here-
unto set our hands.
